LIPSTICK HOLDER

Simon Morrison, New York, N. Y.

Application January 6, 1936, Serial No. 57,650

4 Claims. (Cl. 206—56)

The invention relates to lipstick holders and more particularly to so-called "automatic" lipstick holders. "Automatic" lipstick holders are usually characterized by being operable with one hand to open and close the holder and also advance and retract the lipstick from and into the holder.

Various forms of so-called automatic lipstick holders have been known heretofore, but nearly all of them are undesirably complicated and/or difficult and expensive to satisfactorily manufacture on a production basis. Another frequent difficulty with this type of holder is the presence of one or more points of leakage through which dust creeps in while the holder is being carried loose in a handbag. The trade demands lipstick holders which are rectangular in cross section; and as heretofore constructed, such holders have required various drawn metal members of rectangular cross section, which are not as desirable from a manufacturing standpoint as drawn metal members of circular cross section.

An object of the present invention is to provide an improved automatic lipstick holder of such construction that it is effectively dust-proof and can also be satisfactorily and economically manufactured on a production basis.

Another object of the invention is to provide an automatic lipstick holder which is rectangular in external shape but utilizes for most of its parts drawn metal members which are circular in cross section.

Other objects of the invention will be obvious from the following disclosure, and some of such additional objects relative to details of construction which give the lipstick holder desirable manufacturing or operating characteristics.

Fig. I is a front elevation of a complete lipstick holder embodying the present invention, the holder being shown in closed or carrying condition.

Fig. II is a side elevation of a complete holder in open condition, i. e. with the lipstick projected for use. In the view part of the exterior casing is broken away to show an interior feature.

Fig. III is an enlarged longitudinal section taken on the line III—III of Fig. I.

Fig. IV is an enlarged cross section taken on the line IV—IV of Fig. I.

Fig. V is a front elevation with most of the exterior casing broken away. The parts are shown in the position which they occupy in between the opening of the holder and the projection of the lipstick for use.

Fig. VI is an enlarged front elevation of the holder in closed condition, the exterior casing being removed and various parts being broken away to show concealed structure.

Fig. VII is a perspective view of the exterior casing per se.

Fig. VIII is an enlarged elevation, partially

in section, of an inner tubular member of the holder.

Fig. IX is an enlarged elevation, partially in section, of an outer tubular member of the holder. To save space, a central portion of the member has been broken away in the view.

On the original bristol board drawing filed in the Patent Office Figs. I, II, V and VII are full size showings of an actual embodiment of the invention; Figs. III, VI, VIII and IX are double size illustrations of the same; and Fig. IV is a four to one enlargement of the same. Of necessity, the thickness of thin metal is exaggerated in the drawing, as is usual with sheet metal.

An inner tubular member 1 of circular cross section is provided with a long longitudinal slot 2 having a lateral extension 2^a; it is also provided with a short longitudinal slot 3 which begins at the lower end of the tube and has a lateral intermediate section 3^a. At its upper end, the tube 1 has a pressed out finger 4 which is a closure operating means that will be referred to later. An outer tubular member 6, of circular cross section, is provided with a longitudinal slot 7 and has a pressed out hollow portion 8 in which is pivoted a closure 9. Projecting inwardly from the tube 6 is a stud or pin 10 which may be integral with the tube or attached to it in any suitable way. As shown, the stud 10 is blind riveted to the tube, but it may be soldered or otherwise suitably secured.

Inner tube 1 is telescoped downwardly into outer tube 6, the stud 10 entering and passing along the short slot 3. The slots 2 and 7 are so related that they register with one another when pin 10 is at a point in slot section 3^a. When pin 10 is in the upper straight portion of slot 3 (as is the case when the parts are in the positions shown in Figs. III and VI) slots 2 and 7 do not register, with the result that tube 1 overlaps or closes slot 7.

A lipstick 11 is mounted in a carrier designated as a whole by 12. The carrier consists of a tubular section 13, having an internal bead 13^a, and a cup 14 having a rectangular hole 15 in its bottom. The cup 14 is telescoped against the bead 13^a and is suitably secured to section 13 by friction, solder or otherwise. An exterior, drawn metal, casing 16 is provided with a longitudinal slot 17 and its bottom is closed by a base member 18, secured by friction, solder or otherwise. The upper end of casing 16 is notched at 19 and provided with an inwardly extending flange 20 which leaves a circular aperture 20^a.

After tubular members 1 and 6 have been telescoped together, as previously explained, the lipstick carrier 12 is telescoped inside of tube 1 from either end. This gives an assembly of parts such as is shown in Fig. VI. Then this assembly of parts is telescoped downwardly into

exterior case 16, and projection 8 enters the notch 19. The notch 19 enables the flange portion 20 to expand slightly during the telescoping operation so that the flange 20 may tightly engage the top of tube 6 or even project over it a trifle to secure the parts together. With slots 2, 7 and 17 in alignment, actuator pin 24 may be inserted through the slots and through a hole in tubular section 13. The pin 24 may be attached to the lipstick carrier in any suitable way. As shown, pin 24 is bent upwardly into holding engagement with one corner of the square hole 15. Attached to actuator pin 24 and located on the outer surface of exterior casing 16 is an actuator button 25.

The operation of the holder is as follows: When the actuator button is in its lowermost position the parts are in the position shown in Figs. I, III, IV and VI. Slots 7 and 17 always register with one another, but the extension 2^a of slot 2 permits tube 1 to rotate and cover these slots as shown in Figs. III, IV and VI. To open the holder and project the lipstick for use, it is simply necessary to slide actuator button 25 upwardly. During the initial movement of actuator button 25, actuator pin 24 is held in slot extension 2^a and thus tube 1 is moved upwardly, as well as carrier 12. During this portion of the operation the upper end of tube 1 pushes closure 9 to open position as shown in Fig. V, and the upper portion of slot 3 slides along pin 10. As the position shown in Fig. V is approached, lateral slot section 3^a engages the pin 10 and rotates tube 1 clockwise (viewed as from the bottom of the holder). This rotation of tube 1 brings longitudinal slot 2 in alignment with slots 7 and 17 and also in alignment with actuator pin 24. Thus as the upward movement of actuator button 25 is continued from the position shown in Fig. V, the tube 1 stands still and pin 24 travels up slot 2. Of course, continued upward movement of the pin 24 continues the upward movement of the lipstick and projects it as shown in Fig. II.

Reverse or downward movement of the actuator button 25 retracts the lipstick and closes the holder. When the pin 24 reaches the bottom of slot 2 it starts to move the tube 1 downwardly and the cam action between slot section 3^a and pin 10 rotates tube 1 counter clockwise (viewed as from the bottom of the holder). Pin 24 is now at the closed end of slot extension 2^a and continued downward movement of the actuator button 25 retracts the tube 1, along with the lipstick. As tube 1 approaches its lowermost position finger 4 engages tongue 9^a which is integral with the cover 9 and snaps the cover closed (see Fig. III).

In closed position the cover 9 enters aperture 20^a (see Fig. VII) and rests against the end of tube 6 (see Fig. III), thus the end of the holder is effectively closed against the ingress of dust. Also slot 7 is closed by the non-registration of slot 2 so that dust cannot enter through slot 7.

In compliance with the patent statutes I have disclosed the best form in which I have contemplated applying my invention, but it will be realized that the disclosure is illustrative and that various modifications may be made within the scope of the appended claims.

What is claimed is:

1. A lipstick holder comprising: telescopically

related inner and outer tubular members of circular cross section, both members being longitudinally slotted and the slot in one member having a lateral extension; a closure pivoted to the outer tubular member; a lipstick carrier slidably longitudinally within the inner tubular member; a reciprocatory actuator operable to advance and retract the lipstick carrier; and means to reciprocate and also oscillate the inner tubular member in response to an initial portion of the advancing movement and a final portion of the retracting movement of the actuator, the reciprocating movement of the inner tubular member opening and closing said closure and the oscillating movement uncovering and covering the longitudinal slot in the outer tubular member.

2. A lipstick holder comprising: telescopically related inner and outer tubular members of circular cross section, both members being longitudinally slotted and the slot in one member having a lateral extension; a closure pivoted to the outer tubular member; a lipstick carrier slidably longitudinally within the inner tubular member; a reciprocatory actuator operable to advance and retract the lipstick carrier; means to reciprocate and also oscillate the inner tubular member in response to an initial portion of the advancing movement and a final portion of the retracting movement of the actuator, the reciprocating movement of the inner tubular member opening and closing said closure and the oscillating movement uncovering and covering the longitudinal slot in the outer tubular member; and an exterior casing of rectangular cross section, the exterior casing having an aperture which receives said closure when the same is in closed position.

3. A lipstick holder comprising: telescopically related inner and outer tubular members of circular cross section, both members being provided with long longitudinal slots and said slot in the inner member having a lateral extension, the inner member also having a short longitudinal slot with a lateral section; a closure pivoted to the outer tubular member and arranged to be opened and closed by movement of the inner tubular member; a lipstick carrier slidably longitudinally within the inner tubular member; a reciprocatory actuator having a pin passing through said long longitudinal slots and operable to advance and retract the lipstick carrier; and a projection fixed to the outer tubular member and extending into the short slot in the inner tubular member, the longitudinal portion of the short slot permitting limited reciprocatory movement of the inner tubular member to open and close said closure, and the lateral section of the short slot cooperating with said projection to effect oscillation of the inner tubular member to uncover and cover the longitudinal slot in the outer tubular member.

4. A lipstick holder comprising: an exterior casing, the casing being closed at the bottom and having at the top an inwardly extending flange and a downwardly extending notch; a tube having a struck-out projection adjacent to its upper end; a closure for the tube, the closure being hinged to said projection and the tube being telescoped within said casing with said projection located in said notch; a lipstick carrier slidably within said tube; and mechanism to actuate the carrier and open and close said closure.

SIMON MORRISON.
